(57) CLAIM

The ornamental design for a body blanket with foot pouch and hand warmer sleeves, as shown and described.

DESCRIPTION

FIG. 1 is a front perspective view of a body blanket with foot pouch and hand warmer sleeves, showing my new design;

FIG. 2 is a rear perspective view thereof;

FIG. 3 is a front view of thereof;

FIG. 4 is rear view thereof;

FIG. 5 is a left side view thereof with a right side view being a mirror image;

FIG. 6 is an enlarged top view thereof; and,

FIG. 7 is an enlarged bottom view thereof.

The broken lines are for environmental purposes only and form no part of the claimed design.
